Inventor:

Ernst G. K. Anderson

by James Paddington, Amos Wild
Atlys.

UNITED STATES PATENT OFFICE.

ERNST G. K. ANDERSON, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

RECEPTACLE.

1,245,305.

Specification of Letters Patent.

Patented Nov. 6, 1917.

Application filed January 3, 1916. Serial No. 69,982.

To all whom it may concern:

Be it known that I, ERNST G. K. ANDERSON, a citizen of the United States, residing at Chicago, in the county of Cook and State 5 of Illinois, have invented new and useful Improvements in Receptacles, of which the following is a full, clear, concise, and exact description, reference being had to the accompanying drawing, forming a part of this 10 specification.

My invention relates to receptacles and more specifically to receptacles in which the contacts are electrically dead until an insertible member is introduced in the receptacle.

Among the objects of my invention is to provide such a receptacle which will be simple in construction and reliable in operation.

20 Further objects will appear from the detailed description to follow taken in connection with the appended claims.

In the drawings, in which I have shown one embodiment of my invention—

25 Figure 1 is a face view of the open end of the receptacle;

Fig. 2 is a section on the line 2—2 of Fig. 1;

30 Fig. 3 is a section on the line 3—3 of Fig. 1;

Fig. 4 is a side elevation of the base which supports the binding terminal; and

Fig. 5 is a plan view of Fig. 4.

Referring now to the drawings in detail, 35 the receptacle shown comprises an inner insulating base 10 of suitable material such as porcelain, binding and conducting plates 11 secured to the base 10, clips 12 also secured to the base 10 for holding the parts 40 of the receptacle together and securing them to an outlet box cover, an outer insulating base 13 of suitable material such as porcelain secured in proper relative position to the base 10, and shell and center contacts 14 and 45 15 supported by the base 13. The base 10 is provided with apertures 16 through which the feed wires may extend to a position where they can be engaged by the binding screws 17 which are threaded into the plates 50 11. These plates 11 are securely held on the base 10 by means of hollow rivets 18, the bent over ends 19 of which form contacts

for engagement with suitable contacts supported by the base 13. The base 10 is recessed at 20 to provide clearance for the 55 bent over ends 19 and is also recessed at 21 to accommodate a conducting plate connected with the shell contact 14, as hereinafter described. The base 13 is provided with an annular flange 21^a which, when the device 60 is installed, extends through an opening in the cover plate of the outlet box, and with a center recess 22 to accommodate the shell contact 14. A web or wall 23 extends across the inner end of the base 13 and this web 65 is provided with apertures 24 in which are slidably mounted the eyelets 25 which are electrically and mechanically connected to the shell contact 14. This web 23 is also provided with an aperture 26 through which 70 extends an eyelet 27 which secures the center contact 15 on the base 13. The web is also provided with an opening 28 through which the center contact 15 can extend for engagement with the bent over end 19 of 75 one of the hollow rivets 18. The web is also provided with an opening 29 through which extends an eyelet 30 which secures the conducting plate 31 on the base 13. The web is also provided with a boss 32 forming a backing for the center contact. A conducting plate 33 is secured at its opposite ends to the eyelets 25 and a leaf spring 34 of conducting material is located between the plate 33 and the plate 31 and normally holds 80 35 the shell contact 14 in its innermost position, as shown in Figs. 2 and 3. The ends of this leaf spring 34 are bifurcated as shown at 85 35 to straddle the eyelets 25 to hold the spring in position. The shell contact 14 is 90 cut away as shown at 36 and 37 to avoid short circuiting. The center contact is provided with a stamped-up portion 38 for engagement with the corresponding center contact on the insertible portion, and is 95 provided with a contact finger 39 which extends through the opening 28 in position to be moved to engagement with the bent over end 19 of one of the hollow rivets.

The use of my improved device is as follows: So long as the receptacle is empty the tension in the center contact 15 will hold the contact finger 39 out of engagement with the hollow rivets 18 and the tension in the

spring 34 will hold it out of engagement with the conducting plate 31 so that normally both the shell and center contacts are dead. When, however, a plug or lamp is 5 screwed into the shell contact 14 its center contact will engage the stamped up portion 38 and force the contact finger 39 into engagement with the hollow rivets 18 and will also draw the shell contact 14 outwardly 10 causing the eyelets 25 to slide in the openings 24 and causing the conducting plate 33 to bear on the spring 34 and force the latter into engagement with the conducting plate 31. This establishes a circuit from one of 15 the binding screws 17 through one of the conducting plates 11, one of the hollow rivets 18, center contact 15, lamp or plug circuit, shell contact, eyelets 25, conducting plate 33, spring 34, conducting plate 31, 20 rivet 18, binding plate 11, to the other binding screw 17.

Having thus described my invention what I claim as new and desire to secure by Letters Patent is;—

25 1. A receptacle comprising an insulating base and shell and center contacts supported thereby, said base having a web portion extending across the inner end of said shell contact, said shell contact being secured to said 30 web portion and said web portion forming a backing for the center contact, and a supply contact, said center contact comprising a leaf spring located in the path of an insertible member to be moved thereby into contact 35 with said supply contact, said web portion having an opening through which said center contact extends for engagement with said supply contact.

2. A receptacle comprising an insulating 40 base and shell and center contacts supported thereby, and a supply contact, said center contact comprising a leaf spring located in the path of an insertible member to be moved thereby into contact with said supply 45 contact, said base having two openings therein on opposite sides of the center, said center contact extending through one of said openings for engagement with said supply contact, and securing means for said center 50 contact extending through the other opening.

3. A receptacle comprising an insulating base and shell and center contacts supported thereby, and a supply contact, said base having 55 an opening therein and means for supporting said shell contact for movement with respect to said base comprising a member secured to said shell contact and extending through said opening, and means where- 60 by movement of said shell contact electrically connects it with said supply contact.

4. A receptacle comprising an insulating base and shell and center contacts supported thereby, and a supply contact, said base hav-

ing an opening therein and means for supporting said shell contact for movement with respect to said base comprising a member secured to said shell contact and slidably mounted in said opening, and means whereby movement of said shell contact electrically connects it with said supply contact. 65 70

5. A receptacle comprising an insulating base and shell and center contacts supported thereby, and a supply contact, said base having two openings therein on opposite sides of the center, and means for supporting said shell contact for movement with respect to said base comprising two members secured to said shell contact and slidably mounted in said openings, and means whereby movement of said shell contact electrically connects it with said supply contact. 75 80

6. A receptacle comprising an insulating base and shell and center contacts supported thereby, and a supply contact, said base having two openings therein on opposite sides of the center, and means for supporting said shell contact for movement with respect to said base comprising two members secured to said shell contact and slidably mounted in said openings, and means whereby movement of said shell contact electrically connects it with said supply contact. 85 90

7. A receptacle comprising an insulating base and shell and center contacts supported thereby and a supply contact, said base having an opening therein and means for supporting said shell contact for movement with respect to said base comprising a member secured to said shell contact and extending through said opening, means whereby movement of said shell contact electrically connects it with said supply contact, and a spring for normally holding said shell contact in disconnected position. 100

8. A receptacle comprising an insulating base and shell and center contacts supported thereby and a supply contact, said base having two openings therein on opposite sides of the center, and means for supporting said shell contact for movement with respect to said base comprising two members secured to said shell contact and slidably mounted in said openings, means whereby movement of said shell contact electrically connects it with said supply contact, said means comprising a conductor connecting said two members, and a spring bearing on said conductor to normally hold said shell contact in disconnected position. 110 115 120

9. A receptacle comprising an insulating base and shell and center contacts supported thereby and a supply contact, said base having two openings therein on opposite sides of the center, and means for supporting said shell contact for movement with respect to

said base comprising two members secured to said shell contact and slidably mounted in said openings, means whereby movement of said shell contact electrically connects it with said supply contact, said means comprising a conductor connecting said two members, and a leaf spring bearing on said

conductor and having bifurcated ends for engaging said securing means to normally hold said shell contact in disconnected position. 10

In witness whereof, I have hereunto subscribed my name.

ERNST G. K. ANDERSON.
